CIGARETTE HUMIDOR

Emmett C. Bentley and Wyllis L. Reese,
Abilene, Tex.

Application July 1, 1947, Serial No. 758,260

1 Claim. (Cl. 312—78)

1

This invention relates to a cigarette humidor, and more particularly to a humidor that when opened will move the contained cigarettes into dispensing position, and that when closed will return the cigarettes to a storage compartment within the humidor.

It is a principal object of the invention to provide a humidor that with one movement will open the humidor and at the same time display and dispense the cigarettes. A single movement in the opposite direction will return the cigarettes to their storage compartment and shut the humidor to prevent the ingress of moisture.

A preferred embodiment of the invention is illustrated in the accompanying drawings, but it is apparent that modifications may be made therein without departing from the spirit of the invention as hereinafter claimed.

Figure 1 represents a front elevation of the new and improved humidor in its closed position.

Figure 2 is a similar view, partially in section, showing the humidor in opened position.

Figure 3 is a plan view of the lower portion of the device, showing the cigarettes in dispensing position.

Figure 4 is an elevation, somewhat enlarged, of the clamps for holding the individual cigarettes.

Figure 5 is a vertical section through the upper portion of the vertical standard by means of which the humidor is opened or closed.

The humidor comprises two hemispheres 10 and 11, which in the closed position shown in Figure 1 of the drawings together represent an outline of the world. The lower hemisphere 11 is fixed on a base 13, and the upper hemisphere 10 is fixed to the upper end of a vertically movable sleeve 15.

The sleeve 15 is adapted to slide over a similar and smaller sleeve 16, which in turn is adapted to slide over a rod 17, so that the sleeve 15, the sleeve 16, and the rod 17 constitute a telescoping standard. The rod 17, of course, is stationary, and is secured to the lower hemisphere 11 and the base 13.

A circular container 18 is secured within the lower hemisphere 11, and an annular horizontal carriage 20 is secured to the intermediate sleeve 16. The cigarettes 21 are adapted to be clamped in a plurality of spring clamps 22, which are operable by the sleeve 16 in the vertical movement of the latter to enter or leave the container 18, as will be described more particularly herein-after.

Each clamp 22 comprises two spring arms

5 and a curved central portion 23 that is adapted to be hinged about a horizontal axis. A circular wire spring 25 passes through the curved portion 23 of all the cigarette clamps 22, and the wire spring 25 is secured to the sleeve 16 so as to be vertically movable therewith. Some or all of the clamps 22 also contain small eyelets 26 on their upper arms, and a split wire spring 27 is passed through these eyelets 26 to normally urge the clamps 22 outwardly about their pivot 23. When the sleeve 16 is depressed, it will carry with it the wire spring 25 and the clamps 22. The upper portion of the container 18 is provided with a lip 29 so that as the clamps 22 travel downwardly, the lip 29 will slide along the lower arm of each clamp 22 to facilitate the entrance of the clamp 22 within the container 18, the container 18 being so shaped that it will contain all the clamps 22 vertically when the sleeve 16 is in its lowermost position. During the downward movement of the clamps 22, the arms of the clamps 22 will travel about the pivots 23 to resume a vertical position, and in doing so the clamps 22 will act against the pressure of the wire spring 27. Conversely, 10 when the sleeve 16 is elevated, the clamps 22 will be raised and as soon as the upper portions thereof clear the lip 29 of the container 18, the wire spring 27 will act radially outwardly to tilt the clamps 22 outwardly, as indicated in Figure 2.

15 The lower portion of the upper sleeve 15 contains an aperture 31, in which a ball-bearing 32 is adapted to roll. A spring arm 33 is fastened to the upper portion of the sleeve 15 and bears against the ball-bearing 32 to keep it in engagement with the contained inner sleeve 16. The upper extremity of the inner sleeve 16 contains a slot 35 that has a sharp upper edge and a curved lower edge, as indicated in Figure 5, of the drawings. It will be obvious, therefore, that when 20 the upper sleeve 15 is elevated with respect to the sleeve 16, the ball-bearing 32 will ride on the surface of the sleeve 16 until it engages in the slot 35 at the upper extremity of the sleeve 16. The ball-bearing 32 will then be caught in the slot 35, and the sleeves 15 and 16 will then be locked against further relative movement. If, however, 25 the upper sleeve 15 is depressed, the ball-bearing 32 will readily leave the slot 35 and permit the sleeve 15 to be lowered over the surface of the sleeve 16.

30 Relative movement of the sleeve 16 and the rod 17 is similarly affected by means of a spring arm 43, which is fixed to the sleeve 16, a ball-bearing 44, which rides in a slot in the lower end

of the sleeve 16, and a slot 45, which is in the upper end of the rod 17.

In the operation of the device, a decorative knob 50 secured to the top of the upper hemisphere 10 may be grasped to raise the hemisphere 10 and to expand the telescoping members 15, 16, and 17. The carriage 20 will ride with the sleeve 16, and the clamps 22 will be spring pressed outwardly by the spring 21 to dispensing position.

When the upper hemisphere 10 is depressed, the clamps 22 will be folded inwardly by the lip 29 on the container 18, as hereinbefore mentioned, against the pressure of the spring 21, until all the clamps 22 are positioned vertically within the container 18. To avoid contact of the upper hemisphere 10 with the cigarettes, and possible crushing of the latter, the slot 45 in the upper portion of the rod 17 is given a smoother lower curve than the similar lower portion of the slot 35 in the upper portion of the sleeve 16, so that the sleeve 16 will slide over the rod 17 before the sleeve 15 slides over the sleeve 16. Thereby the cigarettes 21 will be safely contained within the container 18 before the upper hemisphere 10 approaches the lip 29 of the container 18.

Any desired number of cigarettes 21 may be positioned within the container 18. As shown herein, there are sixteen such cigarettes 21 and clamps 22. If desired, an inner ring of clamps 52 may be positioned within the clamps 22. These inner clamps 52 are, like the outer clamps 22, pivoted on a horizontal ring secured to the carriage 20, and a spring 27' similar to the spring 21 will pivot the clamps 52 to dispensing position when the humidor is opened. Depending on the positioning of the inner clamps 52, they will be guided by the outer clamps 22 or the lip 29 of the container 18 when the device is depressed to closing position. In the closed position of the humidor, the inner clamps 52 and their cigarettes will be positioned within the container 18 in a circle smaller than that of the outer clamps 22. Thus, for example, the inner clamps 52 may comprise nine elements.

What is claimed is:

1. A cigarette humidor, comprising a container open at the top, a rod fixed to said container and extending axially upwardly thereof, a sleeve telescopically slidably upwardly and downwardly on said rod, a cigarette carriage fixed to said sleeve and movable therewith to and from an upwardly extended cigarette dispensing position and a retracted cigarette storing position inwardly of said container, a spring loaded latch carried by one of said sleeves and rod to limit telescopic movement of said sleeve in an upward direction, a second sleeve telescopically slidably upwardly and downwardly on said first-mentioned sleeve, a closure for said container fixed to said second sleeve and movable therewith to and from open and closed positions relative to said container, a second spring loaded latch carried by one of said sleeves to limit movement of said second sleeve in an upward container opening direction, said latches being releasable upon downward pressure on said cover when the same is in said open position, and said first-named latch being formed to release prior to said second latch whereby said carriage is retracted into said container prior to downward movement of said second sleeve relative to said first mentioned sleeve.

EMMETT C. BENTLEY.
